(57) **CLAIM**

The ornamental design for an antenna, as shown and described.

DESCRIPTION

FIG. 1 is a front view of an antenna of the present invention; FIG. 2 is a first side view thereof; FIG. 3 is a second side view thereof; FIG. 4 is a rear view thereof; FIG. 5 is a top view thereof; FIG. 6 is a bottom view thereof; FIG. 7 is a front view of the antenna of FIG. 1 in an alternate environment; FIG. 8 is a first side view thereof; FIG. 9 is a second side view thereof; FIG. 10 is a rear view thereof; FIG. 11 is a top view thereof; and, FIG. 12 is a bottom view thereof.

The ornamental design which is claimed is shown in solid lines in the drawings. Any broken lines in the drawings are for illustrative purposes only and form no part of the claimed design.
